United States Patent Office

Des. 210,345

Patented Feb. 27, 1968

210,345

ELECTRIC SHAVER OR SIMILAR ARTICLE

David Eberhart, Bound Brook, N.J., assignor to Ronson Corporation, Woodbridge, N.J., a corporation of New Jersey

Filed Jan. 23, 1967, Ser. No. 5,532

Term of patent 14 years

(Cl. D95—3)

Fig. 4.

Fig. 5.

Fig. 6.

FIG. 1 is a perspective view of the right side of an electric shaver or similar article showing my new design.

FIG. 2 is a perspective view of the left side thereof.

FIG. 3 is a perspective view taken from the top.

FIG. 4 is a top view.

FIG. 5 is a bottom view.

FIG. 6 is a right side view.

FIG. 7 is a left side view.

FIG. 8 is a front view.

FIG. 9 is a rear view.

FIG. 10 is a plan view taken along the arrow shown in FIG. 7.

I claim:

The ornamental design for an electric shaver or similar article, substantially as shown.
